DRILL BIT

Filed April 3, 1924

INVENTOR.

Henry H. Cassriel

BY

Carl P. Griffin
ATTORNEY.

Patented Jan. 11, 1927.

UNITED STATES PATENT OFFICE.

HENRY H. CASSRIEL, OF COALINGA, CALIFORNIA.

DRILL BIT.

Application filed April 3, 1924. Serial No. 703,969.

This invention relates to a bit for standard drill rigs intended to enable a specimen of the rock being drilled in to be taken to the surface.

Another object of the invention is to provide means whereby it will be unnecessary to use the sampling mechanism if no sample is desired, the bit then being used merely as the ordinary bit is used.

Another object of the invention is to provide means for ejecting the sample from the drill when it has been packed tightly therein.

Other objects of the invention will appear as the description proceeds.

An embodiment of the invention is shown in the accompanying drawings in which the same reference numeral is applied to the same portion throughout, but I am aware that there may be modifications thereof.

Fig. 1 is a vertical sectional view of the drill bit,

Fig. 2 is a view of the spring used to eject the sample from the drill bit,

Fig. 3 is a vertical section of the drill bit showing the spring and center in place when no sample is to be taken,

Fig. 4 is a vertical section of the drill with the center up to take a sample of the bottom,

Fig. 5 is a cross-section of the drill bit on a larger scale,

Fig. 6 is a cross-section of the drill,

Fig. 7 is a larger scale view of the center retaining pin,

Fig. 8 is a view in elevation of the drill center plug,

Figs. 9 to 13 are side elevations of different forms of drill bits used in the place of the center plug when no sample is to be taken, and

Figs. 14 to 18 are plan views of the bottom of the bits shown in Figs. 9 to 13.

Fig. 19 is a side elevation of the tool used for driving the pin 6 out, and for reaming the holes when reaming becomes necessary.

The drill bit 1 has the usual water-ways 1', 1'', and is a hollow cylinder for a portion of its length, and is solid for the remainder of its length, there being a threaded coupling lug 2 at the upper end. The drill is sharpened in the usual manner at the lower end, and has two pairs of aligned round holes therein at 3 and 4 and a pair of elongated holes at 5.

The holes 3 and 4 are for the purpose

of receiving the taper pin 6 to retain the drill center either in the position shown in Fig. 3 or in the position shown in Fig. 4, the latter being the position in which the center is placed when a sample is to be removed from the well.

The drill center plug 7 has a hole at 8 and it is provided with a shank 9 which is small enough to pass inside the spiral spring 10, and of such a length that it will touch the drill at the top of the hole therein when the spring 10 is fully compressed. It is the object to have the shank 9 touch the drill when the spring is compressed to prevent injury to the spring as well as to prevent undue shearing on the pin which is then inserted in the hole to hold the center in place.

If a sample of the bottom of the well is to be taken, the drill is arranged as shown in Fig. 4 with the pin holding the center plug up.

The drill is then operated in the usual manner, and as the bottom is cut the hole in the drill is gradually tightly packed full of the bottom drillings. After a suitable time has passed to fill the hole the drill may be pulled up and the pin 6 removed, whereupon the spring will force the drillings forming the packed core out of the drill to be examined.

When the samples are to be taken, often the plug 7 is secured in place with the pin 6 as shown in Fig. 3, the drill is used in that condition until the sample is to be taken, when the plug is raised as shown in Fig. 4. The small bits may also be used without removing the plug, if desired, by simply securing them in the drill when the plug is raised as shown in Fig. 4.

If no samples are to be taken, the drill bits shown in Figs. 9 to 18 may be used. These bits of different shapes on their cutting ends, may be triangular, as shown at 15, square, as shown at 16, chisel-shaped, as shown at 17, pointed, as shown at 18 or rose-shaped, as shown at 19, but in each instance there is a shoulder 20 to bear on the bottom of the drill, and a shank 21 with a hole to correspond with the holes of the drill at 4.

Since these bits are intended for continuous, heavy use, it may happen that the pounding the drill is given may partially shear the pin 6, or in some way fix the small bits so tightly in the hole that they cannot be easily removed, in which event a heavy

wedge may be placed in the elongated holes at 5 to force the bits out of the drill.

In Fig. 19 there is illustrated a tool which is a combined punch and reamer, which is used for the purpose of driving the pin 6 out of the drill. The handle 25 is in the shape of a hammer with a long pointed end, while, what appears to be the handle of the hammer at 26 is a reamer for smoothing up the holes of the drill bits or the holes of the drill 1 should they become hammered due to long usage.

What I claim is as follows, but modifications may be made in carrying out the invention shown in the drawings and in the above particularly described form thereof, within the purview of the invention as defined by the annexed claims.

1. A drill bit of the character described, comprising a hollow drill, a closure for the opening in said drill, a spiral spring in said opening and means to secure said closure

flush with the end of the drill or in a position to compress said spring.

2. In a drill of the character described, a drill having a longitudinal opening therein, a closure for said opening, a spiral spring in said opening and means to secure said closure flush with the end of the drill, or in a position to compress said spring the closure having a shank extending into the spiral spring.

3. A drill of the character described, comprising a drill having an opening extending longitudinally therewith and having transverse openings therethrough, a closure for the longitudinal opening, a spring in said opening and a pin to secure said closure flush with the end of the drill or with the spring compressed whereby an opening for the collection of samples is produced.

In testimony whereof I have hereunto set my hand this 1st day of March, A. D. 1924.

HENRY H. CASSRIEL.
